(57) **CLAIM**

The ornamental design for a brick, as shown and described.

DESCRIPTION

FIG. 1 is a front perspective view of a brick in accordance with the present invention;

FIG. 2 is a rear perspective view of the brick of FIG. 1;

FIG. 3 is a top view of the brick of FIG. 1;

FIG. 4 is a bottom view of the brick of FIG. 1;

FIG. 5 is a rear elevational view of the brick of FIG. 1;

FIG. 6 is a front elevational view of the brick of FIG. 1;

FIG. 7 is a first side elevational view of the brick of FIG. 1; and,

FIG. 8 is a second side elevational view of the brick of FIG. 1.

The claimed brick design is not limited to any particular scale. As indicated in the title, the article of manufacture to which the ornamental design has been applied is a brick (e.g., a ceramic brick, a building brick, a refractory brick, a stone brick, a composite brick).

1 Claim, 2 Drawing Sheets
